ELECTRICAL SWITCH

Olav Froland, St. Louis, Mo., assignor to James R. Kearney Corporation, St. Louis, Mo., a corporation of Missouri

Application August 29, 1941, Serial No. 408,790

9 Claims. (Cl. 200—48)

This invention relates generally to electrical switches and more specifically to heavy duty electrical switches of the rotating insulator type, the predominant object of the invention being to provide an electrical switch of this type which, because of its improved construction and arrangement, is capable of performing its intended function in an improved and highly efficient manner.

Fig. 1 is a side elevation of the improved switch, parts of the insulators thereof being broken away to permit of the switch being illustrated on a larger scale than would be otherwise possible.

Fig. 2 is a plan view of the switch illustrated in Fig. 1.

Fig. 3 is a fragmentary, enlarged vertical section taken on the staggered line 3—3 of Fig. 2.

Fig. 4 is a cross-section taken on line 4—4 of Fig. 3.

Fig. 5 is an enlarged cross-section taken on line 5—5 of Fig. 2.

Fig. 6 is a view similar to Fig. 3 but showing parts of the switch in moved positions.

Fig. 7 is a fragmentary sectional detail illustrating the manner of supporting the switch blade of the switch for rotary movement.

Fig. 8 is a cross-section taken on line 8—8 of Fig. 7.

In the drawings wherein is shown for the purpose of illustration, merely, one embodiment of the invention, A designates the improved switch generally. The switch A includes a base structure 1 which is adapted to be supported by suitable supporting means (not shown) to locate the switch in a desired position for use.

Secured to the base structure 1 and extended upwardly therefrom is a supporting member 2 which supports a stationary insulator 3. The insulator 3 has fixed thereto at its top a member 4 which at its forward end is provided with a horizontal wall 4a through which suitable fastening devices 5 are extended for the purpose of securing the member 4 to the insulator 3. The member 4 is provided with spaced side walls 6 which project upwardly from the horizontal wall 4a and extend horizontally in a rearward direction, said member 4 at a point adjacent to its rear end being provided with a solid, top wall portion 7, as shown to the best advantage in Fig. 2. Extending transversely of the member 4 from one to the other side wall thereof is a pair of transverse walls 8 which aid in imparting the required structural strength to said member 4. At its extreme rear end the member 4 is provided with a downwardly curved portion 9 and the

side walls of said member 4 are joined at their rear ends by a horizontally disposed wall 9'.

Supported by the base structure 1 of the switch A is a bearing member 10 and disposed vertically and extended through said bearing member 10 is a rotary spindle 11, said bearing member preferably, having arranged therein a suitable ball bearing assembly (not shown) which provides for free rotation of the spindle 11 with respect to the bearing member 10. The spindle at its lower end extends downwardly beyond the bearing member 10 and said exposed lower end portion of the spindle is adapted to have secured thereto suitable operating means (not shown) which may be actuated to rotate the spindle 11. At the upper end of the spindle 11 a connecting member 12 is secured thereto or formed thereon, said connecting member rotating with said spindle when it is subjected to rotary movement.

Mounted on and secured to the connecting member 12 by means of fastening elements 13 is an insulator 14 which rotates with the spindle 11 and the connecting member 12, and extended upwardly from the upper end of the insulator 14 is a spindle 15 (Fig. 3) which passes through a bearing member 16 that forms a part of the solid top wall portion 7 of the member 4. The spindle 15 is provided with a lower portion that includes a plate 15a and the spindle is secured to the insulator 14 by fastening devices 17 which pass through openings formed through the plate 15a and are seated in openings formed in the insulator. The bearing member is provided with a shoulder 16' which supports a ball bearing assembly 18, said ball bearing assembly contacting also with an annular raised portion 15' formed on the spindle 15. The ball bearing assembly 18 is maintained in position by an annular flange 19 of a member 20, said member 20 being mounted on and pinned to a screwthreaded portion 21 of the spindle 15 and being so shaped and arranged that it overlies and closes the upper end of the bearing member 16. The extreme upper end portion of the spindle 15 is preferably non-circular in shape, as shown in Fig. 2, and this non-circular spindle portion has clamped, or otherwise secured thereto, an arm 22.

Pivoted to the forward portion of the member 4 is an arm structure 23 which, when viewed in plan as shown in Fig. 2, is of substantially U-shaped formation, in other words the arm structure 23 includes parallel side portions 23a, a straight, forward portion 23b of increased thickness, and inclined portions 23c which join the side portions and the straight, forward portion.

As shown in Fig. 2 forward portions 24 of the spaced side walls of the member 4 are offset inwardly relative to adjacent portions of said spaced, side walls of said member 4, and rearwardly located portions of the side portions 23a of the arm structure 23 are arranged in outward, overlapping relation with respect to said offset portions 24 of the member 4. The side portions 23a of the arm structure 23 and the offset portions 24 of the member 4 are provided with related, contacting boss portions, and a pivot pin 25 is extended through openings formed through said side portions of the arm structure and said offset portions of the member 4 so as to pivotally attach said arm structure 23 to said member 4. Also the arm structure 23 includes a transverse wall 26 which extends from one side portion to the other thereof as shown in Figs. 2 and 3.

Supported by the arm structure 23 is a switch blade 27 which is in the form of an elongated, tubular element, the forward portion of said tubular element being flattened as shown at 28 in Figs. 1, 2, 5, and 6. The tubular element which provides the switch blade 27 is supported in openings formed through the front portion 23b and the transverse wall 26 of the arm structure 23 in a manner to permit of rotary movement of said switch blade relative to said arm structure. Also, the portion of the switch blade 27 which is located between the forward portion 23b and the transverse wall 26 of the arm structure has mounted thereon a sleeve 29, said sleeve at its forward end abutting against the inner face of the forward portion 23b of the arm structure and at its rear end abutting against the forward face of a boss 26' formed on the transverse wall 26 of said arm structure. The sleeve 29 is rigidly secured to the switch blade 27 through the instrumentality of a pin 30, and because of this fact and due to the interposition of the sleeve between parts of the arm structure 23 as described above, the switch blade may not move longitudinally of its axis with respect to said arm structure.

Disposed immediately above the rear portion of the arm structure 23 and the forward portion of the member 4 is a connecting member 31 which comprises an elongated bar 32 which supports at its forward end a pair of spaced plates 33. The bar 32 and the spaced plates 33 of the connecting member 31 are preferably formed integral with each other, and because the bar 32 is narrower than the space between the inner faces of the spaced plates 33 opposed webs 34 extend from the opposite side faces of the bar to said inner faces of the spaced plates, one of said webs being shown in each of Figs. 3 and 6.

The connecting member 31 is supported by a pair of links 35 and a pair of links 36, the elongated bar 32 of said connecting member 31 being disposed between the upper ends of the links of said pairs of links. The links 35 are pivotally connected at their upper ends to the bar 32 of the connecting member 31 by a pivot pin 37 which passes through apertures formed through the upper end portions of the links and through the bar 32, and at their lower ends said links 35 are provided with hub portions 35' through which the previously mentioned pivot pin 25 extends, said hub portions of said links 35 being rotatable with respect to said pivot pin 25 and the outer end faces of said hub portions being in contact with portions of the offset portions 24 of the member 4. The rear end of the bar 32 of the connecting member 31 is provided with a

transversely extended portion 38 which extends outwardly from the opposite side faces of said bar, and this portion 38 is disposed between the upper end portions of the links 36, there being a pivot pin 39 which is disposed in aligned openings formed through the portion 38 and the upper end portions of the links 36 for pivotally connecting the upper portions of the links and the connecting member 31. The lower end portions of the links 36 are provided with hub portions, and said lower end portions of said links are disposed between parts of the side walls of the member 4 and extensions 40 (Fig. 2) that are projected inwardly and rearwardly from the offset portions 24 of said member 4, said extensions 40 including upwardly projected portions 40' (Fig. 3) which provide bearing portions for the inner end portions of pivot pins 41 that are supported at their outer ends in bearing openings formed in the side walls of the member 4 and which pivotally support the lower portions of the links 36.

Disposed between the spaced plates 33 of the connecting member 31 is an element 42 which is pivoted to said spaced plates by a horizontal pivot pin 43. The element 42 has pivoted thereto also the forward end portion of a rod 44, a vertically disposed pivot pin 45 being employed to effect pivotal connection between the forward, bifurcated end portion of said rod 44 and the element 42. The rear end portion of the rod 44 is likewise bifurcated and this end portion of said rod is pivotally connected to an element 46 through the instrumentality of a horizontal pivot pin 47, and said element 46 is supported for rotary movement about a vertical pin 48 which is fixedly supported by the forward portion of the arm 22.

The wall 26 of the arm structure 23 has formed thereon a pair of forwardly extended ears 49 to which are pivotally attached by means of pivot pins 50 a member 51. The member 51 includes an upper portion 52 which is disposed between forward portions of the spaced plates 33 of the connecting member 31 and which is pivoted to said spaced plates by a pivot pin 53, and said member 51 includes a bifurcated, lower portion 54 the spaced legs of which are disposed between the ears 49 and adjacent portions of the side walls of the member 4, the pivot pins 50 being supported in aligned apertures formed in said ears and in said adjacent portions of the side walls of said member 4 and passing through openings formed through the spaced legs of said member 51. One of the spaced legs of the bifurcated portion of the member 51 is provided with an inwardly projected extension 55, and extended forwardly from said extension 55 is a rod 56. The rod 56 extends between spaced apart prongs 29' formed on the previously mentioned sleeve 29 which is fixed to the switch blade 27 as shown to good advantage in Figs. 3, 4, and 6. In order to make good electrical connection between the switch blade 27 and the member 4 a plurality of flat, flexible cables 57 are secured to the wall of the switch blade and to an integral, upstanding extension 58 formed on the horizontal wall 4a of said member 4, the forward portions of the cables 57 being secured to the wall of the switch blade by a pair of bolts 59 and a plate 60, as shown in Fig. 7, and the rear portions of said cables being secured to the extension 58 of the member 4 by a bolt 61.

Secured to the base structure 1 of the improved switch at the forward end thereof is a supporting

member 62 which has fixed thereto and supports an insulator 63. Secured to the upper end of the insulator 63 by fastening devices 64 is a plate 64 which has formed thereon opposed, upstanding extensions 65 (Fig. 5). The extensions 65 support a pair of opposed contact structures 66, each of which comprises a plurality of heavy wires or rods, possessed of resiliency, which are suitably anchored at their lower ends in openings formed in the extensions 65 and extend upwardly from said extensions to their upper ends where they are bent inwardly and are extended downwardly as shown in Fig. 5. The downwardly extended portions 66' of the wires or rods of the contacts 66, which are free at their lower ends, are spaced inwardly from the associated outer, upwardly extended portions of said wires or rods of the contacts, and said portions 66' of said contacts 66 are spaced from each other a distance slightly less than the width of the flattened portion 28 of the switch blade 27. Secured to the plate 64 is an arcing horn structure 67 which comprises a horizontal loop portion 68 through which a bolt 69 is extended for fastening the arcing horn structure to the plate 64, and spaced, upstanding portions 70 which are flared at their upper ends. Also the switch blade 27 has fixed to its forward end an arcing rod 71 which is adapted to move between the spaced portions 70 of the arcing horn structure on movement of the forward portion of the switch blade 27 into and out of contact relation with respect to the opposed contacts 66.

The horizontal wall 9' of the member 4 has secured thereto, by means of fastening devices 72, a suitable clamp structure 13 which electrically engages a conductor 74 that forms a part of the circuit with which the switch A is electrically associated. Also the plate 64 at the opposite end of the switch A has fixed thereto by means of fastening devices 75 a similar clamp structure 76 which electrically engages a conductor 77 that likewise forms a part of the circuit with which the switch A is electrically associated.

In explaining the operation of the improved switch disclosed herein it will be assumed that the switch is in the closed position, as shown in Figs. 1 and 3, and that it is desired to operate the switch to cause the switch arm 27 thereof to move to the open switch position, as shown in Fig. 6. Such operation of the switch is accomplished by rotation of the spindle 11 through the use of the operating means which is associated with said spindle but which is not shown in the drawings. Rotation of the spindle 11 imparts like rotation to the assembly of parts which includes the supporting member 12, the insulator 14 and the spindle 15, and rotation of the spindle 15 causes the arm 22 to swing in an arc of a circle as indicated by the arrow in Fig. 2. As the outer end of the arm 22 moves through its arcuate path the pin 48 fixed thereto rotates within the member 46 and as the outer end of said arm 22 starts its rearward movement the rear end portion of the rod 44 moves outwardly and rearwardly with the outer end portion of said arm 22, the pivotal connections provided by the pins 48 and 45 at opposite ends of the rod 44 permitting such outward movement of the rear portion of said rod 44.

The initial rearward movement of the forward portion of the rod 44 moves the connecting member 31 rearwardly, the links 35 and 36 which support said connecting member, and which at this time are substantially parallel,

swinging on their pivots as indicated by dotted lines in Fig. 3, to move the connecting member 31 rearwardly in a substantially horizontal position. Such rearward movement of the connecting member 31 carries the upper portion of the member 51 rearwardly to rotate said member about its pivot 50 with the result that the rod 56 of said member 51 will be moved upwardly in contact with the uppermost of the prongs 29' of the sleeve 29 to rotate the switch blade 27. Rotation of the switch blade 29 moves the flattened portion 28 of said switch blade from the horizontal position in which said flattened portion is shown by full lines in Fig. 5 to the dotted line position of said flattened portion of the switch blade as shown by dotted lines in Fig. 5, in which position the opposed edge of said flattened switch blade portion are out of contact with the portions 66' of the contacts 66. Continued rearward, arcuate movement of the arm 22 causes the connecting member 31 to assume constantly changing angular positions because of the linkage provided by the links 35 and 36, with the result that the outer end of the switch blade 27 will be raised until the connecting member 31 and the links 35 and 36 reach their final positions as shown in Fig. 6 where the switch blade is disposed in a vertical position.

When the switch is being operated to move the switch blade from the open position shown in Fig. 6 to the closed position shown in Fig. 1, the operation just described is reversed; that is to say outer end of the arm 22 is moved forwardly in an arc of a circle to lower the outer end of the switch blade 27 through controlling operation of the assembly made up of the connecting member 31 and the links 35 and 36. When the switch blade 27 reaches its lowered position the flattened portion 28 of said switch blade is positioned as shown by dotted lines in Fig. 5, and the final forward movement of the arm 22 causes the connecting member 31 to move forwardly a slight distance in a substantially horizontal position during which movement the member 51 is rotated on its pivot 50 to impart such rotary movement to the switch blade, through contact of the rod 56 of said member 51 with the lowermost of the prongs 29', as will move the opposite edges of the flattened portion 28 of the switch blade into firm contact with the portions 66' of the contacts 66.

1. A switch mechanism comprising a supporting member, an arm structure pivotally connected to said supporting member for swinging movement, an elongated switch blade supported by said arm structure for rotary movement about the axis of said switch blade, opposed contacts between which a portion of said switch blade is adapted for disposition with parts of said switch blade portion in contact with said opposed contacts, and means operable during a single continuous operation thereof to rotate said switch blade to move said parts of said switch blade portion out of contact with said opposed contacts and to swing said arm structure on its pivot to move said switch blade away from said opposed contacts, said means comprising a connecting member pivotally attached to said supporting member, mechanism for subjecting said connecting member to pivotal movement, and an element pivotally supported by said arm structure and pivotally connected to said connecting member, said pivotally supported element including a portion extended between spaced prongs which are fixedly associated with said switch blade and

tacts, and means operable during a single continuous operation thereof to rotate said switch blade to move said parts of said switch blade portion out of contact with said opposed contacts and to swing said arm structure on its pivot to move said switch blade away from said opposed contacts, said means including a connecting member, pairs of links pivotally attached at ends thereof to said connecting member at points spaced longitudinally thereof and pivotally attached at opposite ends thereof to said supporting member at spaced points thereof, mechanism for subjecting said connecting member to movement, and a pivoted element connected to said connecting member and actuated by movement thereof to rotate said switch blade.

9. A switch mechanism comprising a supporting member, an arm structure pivotally connected to said supporting member for swinging movement, an elongated switch blade supported by said arm structure for rotary movement about the axis of said switch blade, opposed contacts

between which a portion of said switch blade is adapted for disposition with parts of said switch blade portion in contact with said opposed contacts, and means operable during a single continuous operation thereof to rotate said switch blade to move said parts of said switch blade portion out of contact with said opposed contacts and to swing said arm structure on its pivot to move said switch blade away from said opposed contacts, said means including a connecting member, pairs of links pivotally attached at ends thereof to said connecting member at points spaced longitudinally thereof and pivotally attached at opposite ends thereof to said supporting member at spaced points thereof, mechanism for subjecting said connecting member to movement, and a pivoted element supported by said arm structure and connected to said connecting member and actuated by movement thereof to rotate said switch blade.

OLAV FROLAND.
